UNITED STATES PATENT OFFICE.

EUGENE DE ROGY, OF NEWARK, NEW JERSEY.

DESIGN FOR A BREASTPIN.

SPECIFICATION forming part of Design No. 22,628, dated July 18, 1893.

Application filed January 28, 1893. Serial No. 460,169. Term of patent 3½ years.

To all whom it may concern:

- Be it known that I, EUGENE DE ROGY, a citizen of the United States, residing at Newark, in the county of Essex and State of New Jersey, have invented and produced a new and original Design for a Breastpin; and I do hereby declare the following to be a full, clear, and exact description of the invention, such as will enable others skilled in the art to which it appertains to make and use the same, reference being had to the accompanying drawings, and to letters of reference marked thereon, which form a part of this specification.
- 5 Referring to said drawings, Figure 1. represents, in front elevation, a bar-pin and a pendant embodying my design and Fig. 2 is a view, also in elevation, of the pendant, showing the opposite side thereof.
- 10 The leading feature of my design as shown in the drawings in which Fig. 1 is a plan view of the same and Fig. 2 is an edge view, consists in the unitary design of a breastpin com-
- prising a bar, and a sphere pendent therefrom. The bar has a sunken central surface and a circular depressed surface at each end. Between the circular ends and the body of the bar are ornaments. On the ball are shown the principal divisions of the globe, the land being in relief and the water depressed, or vice versa.
- 15 A, designates the land, B, the water, and C, an eye.
- d indicates the bar, and e, e, the ornaments between the ends of the bar and the central portion.
- 20 What I claim is—
- The design for a breast pin substantially as herein shown and described.
- In testimony that I claim the foregoing I have hereunto set my hand this 26th day of January, 1893.

EUGENE DE ROGY.
